Charles G. Shauck -
By J. L. Glaser, Secy.

UNITED STATES PATENT OFFICE.

CHARLEY G. SHAUCK, OF DES MOINES, IOWA.

DIRECTION-SIGNAL FOR AUTOMOBILES.

1,276,425.

Specification of Letters Patent. Patented Aug. 20, 1918.

Application filed November 11, 1916. Serial No. 130,793.

To all whom it may concern:

Be it known that I, CHARLEY G. SHAUCK, citizen of the United States of America, and resident of Des Moines, Polk county, Iowa, have invented a new and useful Direction-Signal for Automobiles, of which the following is a specification.

The object of this invention is to provide improved means for indicating through suitable visual signals the direction of contemplated turning of a vehicle in either direction relative to a straight line of advance.

A further object of this invention is to provide improved means for indicating through suitable visual signals projected to the front and rear and at angles relative thereto, of contemplated turning of a vehicle in either direction from a straight line of advance.

20 A further object of this invention is to provide improved means for indicating through suitable visual signals projected both to the front and rear of contemplated stopping or advancing of a vehicle.

25 A further object of this invention is to provide an improved construction for a lamp signaling device.

My invention consists in the construction, arrangement and combination of elements 10 hereinafter set forth, pointed out in my claims and illustrated by the accompanying drawing, in which—

Figure 1 is a diagram illustrating one form of wiring for my improved signal.

5 Fig. 2 is a rear elevation of one form of my improved lamp device. Fig. 3 is a cross-section on the indicated line 3—3 of Fig. 2. Fig. 4 is an elevation, partly in section, of the device shown in Figs. 2 and 3.

0 In the construction of the apparatus as shown the numeral 10 designates a frame preferably made of bar metal and comprising a central body portion and end portions at right angles to the ends of the body portion. A casing is mounted on the frame 10 and is comprised preferably of two members; namely, a body and a door. The body preferably is made of a single piece of sheet metal by stamping and bending and comprises a back 11 arranged parallel and in contact with the outer face of the body of the frame 10, top and bottom end members 12, 13 bent at right angles to ends of the back 11 and extending parallel with and in contact with outer faces of the ends of the frame 10, and central arms 14, 15 extending

at right angles from the central portion of the body 11 and parallel with each other. Marginal portions 16, 17 of the body 11 and marginal portions 18, 19 of the top and bottom end portions of the casing are bent into planes parallel with each other to form flanges which extend across and project slightly beyond the body and ends respectively of the frame 10, thus forming apertured parallel sides for the casing. End portions of the arms 14, 15 are bent inwardly to form flanges 20, 21. A partition 22 is arranged horizontally in and centrally of the frame 10 and one end portion of said partition is secured to the central portion of the body of said frame. The flanges 16, 17, 18 and 19 and the arms 14, 15 are spaced from the side margins of the frame 10. Plates 23, 24, 25, 26 of glass are mounted between the flanges 16, 17, 18, 19 and the side margins of the frame 10. The plates 23 and 25 are parallel with each other and spaced apart and preferably are colored pink or red and are located above the partition 22. The plates 24 and 26 are parallel with each other and spaced apart and preferably are colored green and arranged below the partition 22. Fastening devices such as stove bolts 27 are mounted through and connect the arms 14, 15 and draw said arms toward side margins of the partition 22. The fastening devices also may extend through the glass plates if desired. The outer end portion of the end 12 of the casing is bent downwardly to form a flange 28 which extends across and is spaced from the extremity of the upper end of the frame 10. A door 29 is slidably mounted to form a wall of the casing and is confined by the flanges 20, 21 and 28 in contact with the ends of the frame 10 and the outer end of the partition 22. The outer ends of the flanges 19 also may be bent inwardly across the plane of the door 29 to confine said door in sliding relation with the extremity of the lower end of the frame 10. A roll 30 is formed on the lower end of the door 29 and serves as a handle for manual operation of the door. The end members 12, 13 of the casing are secured to extremities of the ends of the frame 10 by screws 31, 32 and the latter screw also is employed to pivot a button 33 adapted to extend beneath and support the door 29 in closed positions at times. Lamp sockets 34, 35 are mounted on and extend above and below the central portion of the

partition 22 and lamp bulbs 36, 37 are removably mounted in said sockets. A clamp 38 is fixed to and projects laterally from the central portion of the body of the frame 10 and casing 11 and is adapted to engage and support the device on a suitable carrier such as a frame bar 39 of the windshield of an automobile. It is to be understood, however, that the carrier may be any 5 suitable supporting member of any vehicle, such as a top prop or bow of a buggy or a superposed frame of any kind.

The glass plates may be uncolored or plain and the bulbs 36, 37 be differently colored so 10 as to exhibit various colored lights through said plates, hence the matter of coloring the plates or bulbs is one of selection within the scope of my invention.

The signal preferably is illuminated by an 15 electric current from a system arranged as shown in Fig. 1 in which a battery in circuit with the ground at one pole has a conductor 40 leading from the other pole and branching into two conductors 41, 42. The conductor 41 extends through a lamp 37 at 20 one side and through a lamp 36 at the other side and thence is grounded in a suitable manner such as on the frame of the vehicle to which the signal is applied. The conductor 41 is provided with a switch 43. The conductor 42 extends through a lamp 37 on 25 one side and through a lamp 36 on the other side and thence to ground as desired. The conductor 42 is provided with a switch 44.

In practical use of the device it may be 30 assumed that normally the lamps 36, 37, arranged in pairs in the devices as shown on opposite sides of a vehicle and visible to the front and rear and at angles relative to the line of advance, are not illuminated. When 35 it is desired to turn the vehicle to the left the switch 44 is closed, thus establishing a circuit through a green lamp 37 (indicating safety to the right) and through a red lamp 36 (indicating danger to the left).

When it is desired to turn the vehicle to the right the switch 43 is closed, thus establishing a circuit through a green lamp at the left (indicating safety) and a red lamp at 40 the right (indicating danger). Immediately upon effecting a turn in either direction the switch last used is opened, thus discontinuing the illumination. By this means 45 warning or signal is given to any person observing the lamp devices either in front or at the rear of the vehicle on which they are mounted and in line with or laterally removed to some extent from the path of travel of the vehicle, of intended turning of

50 the vehicle in either direction, thus giving good and sufficient notice of the turning to permit one meeting or following it to act on the signal as given and avoid confusion or collision.

55 When the driver of a vehicle equipped

with this device contemplates stopping the vehicle, warning to such effect may be given by closing both switches, thus exhibiting a red signal on each side of the vehicle and putting another traveler on his notice of impending event and also exhibiting on each side of the vehicle a green light indicating to such other traveler that no danger is to be apprehended from the vehicle thus equipped.

70 Or the arrangement of the wiring system and switches may be such as to exhibit red lights on both sides of the vehicle as a signal of stopping or green lights on both sides of the vehicle as a signal of continuation in a straight path.

The bulbs 36, 37 may be removed and replaced or substituted by others through manual operation thereof within the casing when the door 29 is opened by downward 80 withdrawal from the casing.

It is to be understood that the sockets 34, 35 are suitably connected into the electric circuits shown in diagram in Fig. 1 by wiring through the casing or frame of the lamp 90 devices.

It also is to be understood that the lamp devices may be mounted in any suitable location, depending upon the selection of the user.

95 I do not desire to be understood as limiting myself to the details of construction and wiring herein shown and described, as the same may be modified in many particulars without departing from the spirit of my invention.

100 I claim as my invention—

1. A signal lamp, comprising a frame, a clamp thereon adapted to engage a support, a partition on said frame, an apertured casing inclosing said frame and partition, glass plates in some of the apertures of said casing, said plates being arranged parallel with each other and also being arranged on opposite sides of said partition, the plates on one side of the plane of said partition being alike in color and of a color differing from the plates on the opposite side of the plane of said partition, and lamps carried by and on opposite sides of 1 said partition, together with a door adapted to close the remaining aperture of said casing.

1. A signal lamp, comprising a frame, means for supporting said frame, an opaque 1 partition on said frame, an apertured casing inclosing said frame and partition, glass plates in some of the apertures of said casing, said plates being arranged in pairs on opposite sides of the plane of said partition, one pair of plates being colored differently from the other pair of plates, independent lamps carried by and extending oppositely from said partition between the respective pairs of plates, and a door slid-

ingly motinted in the remaining aperture of said casing.

3. A signal lamp, comprising a frame, an opaque partition centrally located on said frame, an apertured casing inclosing said frame and partition and spaced from the margins thereof, glass plates mounted in some of said apertures and slidingly engaged between said casing and side margins of said frame and partition, clamping bolts
- 5 extending through side portions of said casing and adapted to contract the same and draw the plates toward the frame and partition, and a door slidingly mounted in the remaining aperture of the casing, together 15 with lamps between the plates and on opposite sides of said partition.

Signed by me at Des Moines, Iowa, this twenty third day of October, 1916.

CHARLEY G. SHAUCK.
